(No Model.)

A. A. AMBLER.

Odometer.

No. 230,981.

Patented Aug. 10, 1880.

UNITED STATES PATENT OFFICE.

ARTHUR A. AMBLER, OF ST. CLOUD, MINNESOTA, ASSIGNOR OF TWO-THIRDS OF HIS RIGHT TO ALEXANDER F. ROBERTSON AND EDWARD K. JACQUES, OF SAME PLACE, ONE-THIRD TO EACH.

ODOMETER.

SPECIFICATION forming part of Letters Patent No. 230,981, dated August 10, 1880.

Application filed April 16, 1880. (No model.)

To all whom it may concern:

Be it known that I, ARTHUR ALEXANDER AMBLER, of St. Cloud, in the county of Stearns and State of Minnesota, have invented a certain new and useful Improvement in Odometers, of which the following is a specification. This invention relates to odometers, or instruments used in measuring and recording the distances traveled by vehicles of all kinds; and it consists in an endless flexible metal belt arranged to revolve in an oblong case, and combining with an endless ratchet-belt provided with a suitable stud and adapted to be revolved by a tripping-pawl a ratchet-wheel so arranged that the stud on the belt will act upon one of the teeth of the ratchet-wheel and cause it to rotate the distance of one tooth during every revolution of the belt, as will be hereinafter more fully set forth.

My invention further consists in combining, with an endless ratchet-belt adapted to be revolved by a tripping-pawl, a ratchet-wheel, a disk provided with a cavity and tooth, and a lock-gear, whereby one revolution of the ratchet-wheel and disk will revolve the gear the distance of one of its teeth and hold it locked at all other times, as will be more fully and in detail explained.

I attain these objects by the mechanism illustrated by the accompanying drawings, in which—

Figure 1 is a perspective view, with the cover, hands, dials, &c., removed and a portion of the casing broken out to show the arrangement of the interior mechanism. Fig. 2 is a plan view of the outside of the odometer, showing the arrangement of the dials, &c. Fig. 3 is a longitudinal section of the rear portion of the odometer. Fig. 4 is a detached detail view of a portion of the ratchet-belt and ratchet-wheel, illustrating the manner in which the former acts upon the latter; Fig. 5, a detached detail view of a portion of the ratchet-belt and the tripping-dog, showing a variation in the method of construction of the latter; Fig. 6, a plan view, with the cover removed, of a portion of the front end of the odometer, showing a variation in the method of operating the tripping-dog, &c. Fig. 7 is a

rear elevation, reduced, of a portion of an axle and hub of a buggy having my device attached thereto, showing the method of applying the odometer.

Figs. 1, 2, 3, 4, 5, and 6 (in the original drawings) are two times the natural size, while Fig. 7 is drawn to a scale of one and one-half inch to the foot.

A is the casing, in the forward end of which a bar or shaft, B, is arranged to project a short distance beyond the end, at *a*, and provided with a coiled spring, *b*, by which it is held outward, or returned outward when pushed in, as hereinafter explained.

In the opposite end of the casing A a pulley, C, is pivoted, around which an endless metal belt, D, is arranged, the other end of which extends backward about two-thirds the length of the casing A, as shown in Figs. 1, 2, and 3, with its sides running against the sides of the casing. In this position the belt may be revolved easily by any power applied to its periphery, as hereinafter explained. The upper edge of this belt D will be supplied with ratchets or teeth *c*, as shown, and provided with a spring-pawl, *d*, arranged to catch upon the teeth *c* and prevent the belt being turned backward.

E is a rod connected to the shaft B, and having a spring-dog, *e*, adapted to catch upon the teeth of the ratchet-belt, so that when the shaft B is pushed inward the dog *e* will be forced backward over the teeth *c*, (the latter not being affected by this action, as they are held by the pawl *d*), and when the spring *b* forces the shaft B outward again the dog *e* will catch in the teeth *c* and revolve the belt D the distance of one of its teeth.

F is a ratchet-wheel mounted in the casing upon a shaft, *f*, just forward of the pulley C, with one side close to one side of the belt D, so that a stud or pin, *g*, projecting from the inside of the belt D will catch upon one of the teeth of the ratchet-wheel F as the belt is carried past it when being revolved by the dog *e*, and thus cause the ratchet-wheel to be revolved the distance of one of its teeth once in every revolution of the belt D.

Above the ratchet-wheel F, and upon the

same shaft t' , and arranged to revolve with it, is a circular disk, G, on the same plane as a lock-gear, H, which is mounted upon a shaft, t^2 , in the casing A, and having ten (10) spaces 5 h , and ten (10) concave teeth, i , between them, the radii of the curves of said concaves being one-half of the diameter of the disk G, so that when placed with one of the concave teeth i against the edge of the disk G the latter will 10 be free to revolve, but the former will be locked and prevented from turning, as shown in Fig. 1.

At one point in the rim of the disk G a 15 semicircular cavity, k , is formed, and a tooth, m , inserted therein and adapted to enter one of the spaces h of the gear H, and carry it around the distance of one of its teeth i , the corners of the teeth i on either side of the space h being acted upon by the tooth m entering the cavity k , which is made for that 20 purpose, and thus bring the concave surface of the next tooth i in contact with the smooth portion of the disk G, thus revolving the gear H the distance of one of its teeth once in 25 every revolution of the disk G, and holding them locked together at all other times.

I is a second disk, precisely like disk G, mounted on the same shaft t^2 as the gear H, and arranged to revolve with it; and K is a second lock-gear, precisely like gear H, mounted 30 upon a third shaft, t^3 , and adapted to be acted upon by the disk I and its tooth n and cavity p , exactly as disk G and its tooth m and cavity k acts upon the gear H, so that one revolution 35 of the gear H and disk G will move the gear I the distance of one of its teeth.

By this arrangement one revolution of the 40 belt D revolves the ratchet-wheel F and disk G the distance of one tooth, and one revolution of the ratchet-wheel and first disk revolves the first lock-gear, H, and second disk, I, one tooth, while one revolution of these latter 45 revolve the second lock-gear, K, the distance of one of its teeth; so that if the ratchet-wheel F contains twenty teeth and each of the lock-gears ten teeth, as in the drawings, twenty complete revolutions of the belt D will revolve the ratchet-wheel once, and with it the disk G, and ten complete revolutions of the ratchet-wheel F and disk G will revolve the gear H and disk I once, and ten complete revolutions of the gear H and disk I will revolve the gear K once; so that ten revolutions of the gear H and disk I, and one hundred revolutions of 55 the disk G and ratchet-wheel F, and two thousand revolutions of the belt D will be necessary to revolve the gear K once.

The shafts t' t^2 t^3 of these wheels and disks F, G, H, I, and K project upward through 60 the cover M of the casing A, and are provided with hands or pointers N' N^2 N^3 , around each of which circles are formed in the face of the cover M, and graduated by figures from 0 to 9, to correspond to the teeth in the gears H and K and ratchet F, there being intermediate 65 graduations between the figures on the dial above the latter to correspond to the ex-

tra ten teeth therein. By this means the hands N' N^2 N^3 will denote on the face of the casing the positions of the wheels below, and also record the number of their revolutions. 70

The figures U T H on the dials in Fig. 2 denote units, tens, and hundreds.

A hinged cover, P, (see Fig. 7,) will be attached to the instrument to protect the dials 75 and hands from injury.

To apply the instrument to vehicles, a small cam, r , is attached to the inside of the hub L, (see Fig. 7,) and the odometer secured to the axle R by clamps of any suitable kind in such 80 a position that the revolution of the wheel will cause the cam r to strike the end a of the shaft B, and force it inward once at every revolution, thus acting, as before described, upon the endless belt D and train of wheels F G H 85 I K. The circumference of the vehicle-wheel to which the instrument is to be applied is first carefully measured, and the number of times this dimension is contained in the number of feet in a certain distance (ordinarily 90 two thousand six hundred and forty, or one-half mile, which is the most convenient) ascertained. Then the ratchet-belt D, which is first formed in a long strip of spring-steel or 95 other suitable metal, with teeth c about one twenty-fourth of an inch long, is cut off at the tooth corresponding to the number of times required for the driving-wheel to revolve in traveling the one-half mile or other certain 100 distance above referred to, and the ends brazed or otherwise secured together to form it into a smooth jointless belt. The belt is then placed around the pulley C, and along the sides of the casing A, as shown, and the dog and pawl d e set in place. 105

By this means it will be seen that one revolution of the belt D will be equivalent to one-half mile travel of the vehicle; hence every time the hand N' on the ratchet-wheel shaft t' is moved the distance of one graduation of the 110 first dial the vehicle will have traveled one-half a mile, and every time the hand N' makes one full circuit of the first dial the second hand, N^2 , will have moved the distance of one graduation of its dial, denoting that the vehicle 115 has traveled twenty half miles (there being twenty teeth in the ratchet F) or ten full miles; and when the second hand, N^2 , has made one full circuit, the third hand, N^3 , will have moved the distance of one of the graduations of its dial, thus denoting that the vehicle 120 has traveled one hundred full miles; and then, when the third hand, N^3 , has completed one full circuit of its dial, the vehicle will have traveled one thousand full miles. 125

By my arrangement the parts are contained within a very small space, the whole casing not exceeding seven-eighths of an inch in width, three-eighths of an inch in thickness, and six inches in length, to measure and record one thousand one hundred and ten miles travel; and by adding one more lock-gear and one more toothed disk, like H and I, and one more hand and dial, the scope of the instrument 130

may be increased ten times, or adapted to measure and record eleven thousand one hundred and ten miles, and only adding three-fourths of an inch to the length and nothing 5 to the width or thickness.

In some cases the hub L, after some time of wear, becomes loose and acquires end play, and this frequently causes the cam r to force the shaft B inward farther at some times than 10 at others. To prevent this irregularity of stroke from affecting the instrument injuriously, the under side of the point of the spring-dog e is made inclined, so that when the shaft B is pushed in too far the dog e will simply 15 run up on the pawl d, and not affect the belt D, as the action of the dog on the belt is exerted entirely by its outward stroke; and the shaft B being stopped by the pin u from going beyond a certain point, the belt D will be re- 20 volved just so far at every stroke of the shaft, no matter how far inward it is pushed by the cam r, provided, of course, that it is pushed inward a trifle more than the length of one of the teeth c of the belt D, care being taken in 25 attaching the odometer to the axle to adjust it so that the stroke shall be sufficient to do the work.

Fig. 5 shows a slight variation in the method of connecting the spring-dog e to the bar E, which consists in extending the main bar E the full length and attaching a small inclined spring, v, beneath its inner end, instead of the long spring e, (shown in Figs. 1 and 3,) and in forming an additional slot with an inclined 35 edge through the plate supporting the pawl d, so that when the shaft B is pushed in too far, as before described, the inclined point of the dog e will run up the inclined edge of the slot, instead of up the pawl d, thereby preventing 40 wear or injury to the latter.

Fig. 6 shows a slight variation of the manner of arranging the shaft B and tripping-dog and bar E e. In this arrangement the bar E is extended nearly to the front end of the 45 casing A, as shown, and provided with a spring, w, which throws it backward, and a slot, x', acting in conjunction with a fixed pin, x², in the casing A, to regulate the throw of the bar E, the slot x' being just long enough 50 to allow the bar E to be moved back and forth a little more than one of the teeth of the belt D. Projecting from the side of the bar E, near its outer end, is a pin or stud, y', adapted to be 55 acted upon by a similar stud, y², projecting from the side of the shaft B.

The spring w will be just strong enough to move the bar E backward, but will be much

weaker than the large spring b around the shaft B, so that when the latter is forced inward by the cam r the spring w will carry the 60 bar E inward, and cause the stud y' to follow up the stud y² as far as the slot x' will allow, while the shaft B is free to be pushed as much farther as it will go without affecting the bar E, as the slot and pin x' x² will control the 65 stroke of the dog e, and then, when the shaft B is released, the spring b will cause it to move outward until its stud y² engages with the stud y' on the bar E, and moves the latter outward again, and thus cause the dog e to act 70 upon the belt D. By this arrangement the travel of the bar E is the same, no matter what the throw of the shaft B may be.

The endless ratchet-belt D is a very important part of my invention, as by forming it with 75 the same number of teeth as the circumference of the wheel of the vehicle to which the odometer is attached is contained in any certain distance, the odometer may be adjusted to operate upon any sized wheel.

Under some circumstances it may be found desirable to arrange the endless belt D in a circular form and group the disks and lock-gears within it.

The instrument may be applied to any moving vehicle or machinery, such as carriages, buggies, railroad or street cars, &c., or in any other place where it is desired to ascertain the distance traveled or speed run within a certain time, &c.

What I claim as new is—

1. The combination, with an endless ratchet-belt, D, provided with a stud, g, and adapted to be revolved by a tripping-pawl, e, of a ratchet-wheel, F, so arranged that the stud g 95 will act upon one of the teeth of the ratchet-wheel and revolve it the distance of one of its teeth once in every revolution of the belt, substantially as set forth.

2. The combination, with an endless ratchet-belt, D, adapted to be revolved by a tripping-pawl, of a ratchet-wheel, F, disk G, provided with the cavity k and tooth m, and lock-gear H, whereby one revolution of the ratchet-wheel and disk will revolve the gear the distance of one of its teeth i, and hold it locked at all other times, substantially as set forth.

In testimony whereof I have hereunto set my hand in the presence of two subscribing witnesses.

ARTHUR ALEXANDER AMBLER.

Witnesses:

C. N. WOODWARD,
LOUIS FEESER.
